UNITED STATES PATENT OFFICE.

SOLOMON NARUNSKY, OF BALTIMORE, MARYLAND.

NON-REFILLABLE BOTTLE.

1,216,837.

Specification of Letters Patent.

Patented Feb. 20, 1917.

Application filed January 21, 1915, Serial No. 3,439. Renewed December 13, 1916. Serial No. 136,814.

To all whom it may concern:

Be it known that I, SOLOMON NARUNSKY, a citizen of the United States, residing at Baltimore, in the State of Maryland, have invented certain new and useful Improvements in Non-Refillable Bottles, of which the following is a specification.

This invention relates to improvements in bottle stoppers and has particular reference 10 to that class of bottle stoppers which will permit liquid to be readily poured from the bottle but which will prevent the inflow of liquid to the bottle to such extent as to render the refilling of the bottle commercially 15 impracticable.

The invention consists in the novel construction, combination and arrangement of parts hereinafter described and particularly recited in the claim attached hereto.

20 The invention is illustrated in the accompanying drawing, wherein,—

Figure 1, shows a bottle neck in vertical section with the improved stopper device in place therein,—the latter being shown in 25 side elevation.

Fig. 2, illustrates a bottle neck with the stopper therein,—the casing of the latter being in longitudinal section to disclose the valve parts therein.

30 Fig. 3, shows the bottle neck, stopper casing and valve-parts in central longitudinal section the same being inverted as during the pouring operation.

Fig. 4, illustrates in horizontal sectional 35 plan, the stopper casing and valve parts as they would appear when viewed on the line 4—4 of Fig. 2.

Fig. 5, shows the detached valve parts in perspective, and

40 Fig. 6, illustrates the bottle neck with the stopper therein in top plan.

Referring to the drawing by numerals, 7, designates a bottle neck of ordinary construction and preferably having an exterior 45 annular locking shoulder 8, around its mouth for the engagement of an ordinary well known crown cap.

A stationary cylindric shell 9, has an annular flange 10, around its outer end and is provided with an inner reduced end 11, so as to form an annular shoulder 12, near said inner end. The annular flange 10, has a diameter that permits its snug engagement with the interior of the bottle neck while 55 the main portion or body of the cylindric shell 9 between said outer flange and the

inner reduced end is sufficiently smaller than the neck in diameter to form around the shell an annular space for the reception of a cement 13. Suitable vertical notches 39 14, are provided in the annular flange 10, through which the cement 13, may be readily filled into the space between the neck and shell, and a washer 15, encircles the reduced inner end of the shell and closes 65 the said annular space and prevents the cement from passing down into the bottle during the operation of securing the shell in the neck.

The inner reduced end of the shell has a 70 central flaring passage 16, and at the outer smaller end of said passage said shell has an annular seat 17, on which a circular valve disk 18, may seat when the bottle is in an upright position.

Immediately above the valve seat 17, the interior of the shell has a plurality of upwardly-projecting ribs 19, at the base of which there are annular horizontal shoulders 20,—the shoulders extending from one 80 rib to another as shown in Figs. 3 and 4 of the drawing.

On the interior of the shell and immediately over the valve disk 18, I provide a puppet valve 21, which latter has a cavity 85 22, in its bottom side of sufficient size to receive the valve disk 18, and also has a plurality of side lugs 23, each of which latter has a recess 24, of a size and shape to snugly fit the ribs 19, on the inside of the shell. 90

When the bottle is in an upright position the puppet valve 21, seats on the annular shoulders 20, of the shell and the lugs 23, fit down over the ribs 19, so that a comparatively tight joint is effected between 95 said puppet valve and shell, and at this time the disk valve 18, will be supported on the annular seat 17, beneath the puppet valve to cut off flow of liquid from the upper side of the said valve through the 100 passage 16. The puppet valve has a tapered stop plug 25, projecting from its upper side and is also provided with an annular seat 26, around the base of the said plug for a purpose presently to be described. 105

Around the tapered plug 25, I provide a loose ring 27, with an annular recess or seat 28, at its lower side, of a shape to conform to the seat 26, around the base of the said plug, so that when the bottle is upright this recess 28, of the ring will closely fit the seat 26, on the puppet valve and form 110

another comparatively tight joint. The upper side of the ring 27, carries a packing ring 29, which by contacting with the wall of the shell serves to retard the flow of any liquid between the ring and shell wall when the bottle is upright.

From the foregoing explanation, and by reference to Fig. 2, of the drawing, it will be seen that normally, and when the bottle is in an upright position, the tapered stop plug 25, will project through the ring 27, and extend down above the latter.

Above the projecting end of the tapered plug the interior of the shell contains a baffle member 30, which latter has a plurality of guide lugs 31, around its exterior and also has a recess 32, in its outer or upper side. The under side of this baffle member seats on the pointed end of the stop plug and by reason of its weight aids in pressing the plug and puppet valve down, so as to seat the latter. The guide lugs 31, around the baffle member provide side passages 33, for the passage of liquid during the pouring operation.

An interior shoulder 34, is provided in the shell near the outer end so that a retaining ring 35, may seat thereon and prevent the removal of the stopper parts from the shell. This retaining ring may be cemented in the shell to prevent removal. To facilitate the entrance of air during the pouring operation, I provide a series of passages 36, that extend from the upper side 35 of the retaining ring 35, and open at the lower side thereof.

It will be understood that when the bottle is in an upright position a seal will be formed between the seat 28 of the ring and 40 the seat 26 around the plug; a second seal

will be formed around the bottom of the puppet valve and between the recessed lugs of said valve and the ribs 19, on the inside of the shell and a third seal will be effected by the disk valve 18, seating on the annular seat 17, thereby effectively preventing the commercial refilling of the bottle.

When the bottle is inverted a free passage for the liquid will be provided through passage 16; out through the space between ribs 19; then between the lugs 23, of the puppet valve; through the center of ring 21; then around baffle 30, and through passages 33 and finally out through retaining ring 35.

Sufficient space is left in the shell between the retaining ring and the outer end to permit the insertion of a stopper.

Having thus described my invention what I claim is,—

The combination with a bottle neck, of a shell in said neck said shell having a central passage at its inner end with an annular recess at the outer end of said passage; a disk valve normally in the annular recess; ribs on the inside of the shell at the outer side of the annular recess; a valve having exterior recesses to receive the ribs in the shell said valve having an outwardly-projecting tapered plug; a movable ring around the tapered plug; a retaining ring in the shell near the outer end thereof and a movable baffle in the shell between the end of the tapered plug and the retaining ring.

In testimony whereof I affix my signature in presence of two witnesses.

SOLOMON NARUNSKY.
